(57) **CLAIM**

The ornamental design for a connector, as shown and described.

DESCRIPTION

FIG. 1 is a rear perspective view of a connector showing our new design from one end;

FIG. 2 is a front perspective view thereof from the opposite end;

FIG. 3 is a bottom view thereof;

FIG. 4 is a top view thereof;

FIG. 5 is a left side view thereof;

FIG. 6 is a right side view thereof;

FIG. 7 is a rear view thereof; and,

FIG. 8 is a front view thereof.

The portions of the connector shown in broken lines form no part of the claimed design and are included for environmental purposes only.
